UNITED STATES PATENT OFFICE.

COLUMBUS W. DONNELL, OF FULTON, MISSOURI.

BED-SPRING.

SPECIFICATION forming part of Letters Patent No. 381,060, dated April 10, 1888.

Application filed August 4, 1887. Serial No. 246,129. (No model.)

To all whom it may concern:

Be it known that I, COLUMBUS W. DONNELL, a citizen of the United States, residing at Fulton, in the county of Callaway and State of Missouri, have invented certain new and useful Improvements in Bed-Springs; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 This invention relates to springs and spring bed-bottoms, and has for its object to improve that class of single-coil springs which have their lower ends secured to the slats of the bed and their upper ends interlocked with 20 and mutually bracing each other.

The improvement consists in having the upper end of the spring extended and bent in a series of folds about in the plane of the top of the spring, and having said end bent and brought back beneath the folds midway of 25 their ends and engaged with the spring by having its end extended down within the convolutes of said spring.

The improvement consists in the novel features of construction and combination of parts, 30 which will be more fully hereinafter set forth and claimed, and shown in the annexed drawings, in which—

Figure 1 is a perspective view of two springs 35 embodying my invention; Fig. 2, a plan view of a bed-bottom composed of springs constructed in accordance with my invention; Fig. 3, a sectional view on the line X-X of Fig. 2.

40 The spring is made of a single wire having one end formed into a coil-spring, A, of desired pattern, and the other end bent to form a series of folds, a, about in the same plane as the top of the spring. Said end is projected 45 beyond the folds and forms the interlocking loop a' and the return or supporting arm a'', extended back beneath the folds at right angles thereto and midway of their ends. The inner end of the return or supporting arm is bent down substantially at right angles, and 50 extends within the convolutes of the spring. The folds a fill the gap between the springs

and are supported by the return-arm a''. The lower end of the spring is formed into a clamp by having the end e bent to extend across the 55 lower convolute of the spring. The spring is secured in place by clamping the support, bed-slat, or similar object between said lower convolute and the bent end e.

Figs. 2 and 3 show a bed-bottom composed 60 of my improved springs arranged in parallel lines and having their lower ends secured to the bed-slats B and their upper ends interlocked by having the upper convolute of one spring embraced by the loop a' of the spring 65 next in order.

Having thus described my invention, what I claim, and desire to secure by Letters Patent, is—

1. The herein shown and described spring 70 made of a single wire, having a coil-spring formed on one end, and having its other end bent to form a series of return folds wholly to one side of and about in the plane of the upper convolute of the spring, the interlocking-eye a', to engage with the adjacent spring, the supporting-arm a'', extending beneath and at right angles to the return folds and located midway of their ends, and the downward extension a''' for engaging with the convolutes of 80 the spring, substantially as and for the purpose specified.

2. The herein shown and described bed-bottom, composed of a series of slats, and a series 85 of single springs arranged in parallel lines and having their lower ends clamped to the slats and their upper ends extended laterally in the same direction and bent to form a series of return folds between each two springs and at right angles to the line of springs, and having 90 said extended portion of one spring interlocked with the next adjacent spring and brought back beneath its folds to support them, and having the inner end of said extension bent down and engaged with the convolute of the spring, of which it is an integral part, substantially as described.

In testimony whereof I affix my signature in presence of two witnesses.

COLUMBUS W. DONNELL.
